UNITED STATES PATENT OFFICE

96,931

DESIGN FOR A DRESS

Matty Moskowitz, New York, N. Y.

Application August 1, 1935, Serial No. 57,900

Term of patent 3½ years

To all whom it may concern:

Be it known that I, Matty Moskowitz, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress, showing my new design.

Figure 2 is a rear view of the dress, shown in Figure 1.

The diagonal lines at each side of the shoulder represent inverted tucks.

The shaded lines extending from each tuck at the front portion of the dress represent folds.

The wreath-like ornaments which are connected together by strings of beads represent buckle ornamentations at the neck.

I claim:

The ornamental design for a dress, substantially as shown and described.

MATTY MOSKOWITZ.
